UNITED STATES PATENT OFFICE.

PATRICK KENNEDY, OF NEW YORK, N. Y.

ELECTRIC SIGNALING DEVICE.

No. 824,990.

Specification of Letters Patent.

Patented July 3, 1906.

Application filed March 23, 1905. Renewed February 23, 1906. Serial No. 302,488.

To all whom it may concern:

Be it known that I, PATRICK KENNEDY, a citizen of the United States, residing in the borough of Brooklyn, in the county of Kings, in the city and State of New York, have invented certain new and useful Improvements 5 in Electric Signaling Devices, of which the following is a specification.

This invention relates to the general class 10 of automatic electric signaling devices of the non-interfering kind or type, of which fire-alarm signal-transmitters are examples, and particularly to that form of such transmitters in which the instrument is provided with 15 an auxiliary electromagnet which controls the starting of the signal-transmitting mechanism, but which is normally shunted out of the line-circuit, and therefore inoperative. The main or line electromagnet in the instrument, which is made potentially operative 20 by the pressing in of a signal-transmitting button, serves to break the shunt about the auxiliary magnet and allow the current to flow through its coils only when the line is 25 receptive to the signal to be sent by the instrument.

The present invention relates to means whereby the movements of the armature of the main or line magnet serve to set in motion 30 or arrest a mechanism which acts to break the shunt about the auxiliary magnet, and this device will be hereinafter described with reference to the accompanying drawings, wherein—

Figure 1 is a side elevation of the mechanism shown as it appears when the shunt about the auxiliary magnet is broken. Fig. 2 is a similar view showing the parts of the mechanism in the position they occupy when 40 no current is flowing through the coils of the principal magnet.

In the drawings are shown only the parts of a fire-alarm signal-transmitting mechanism embodying and co-operating with the features of the present invention, but instruments of this general character are known to those skilled in the art.

In the present case, E designates the main or line electromagnet; E', the auxiliary magnet, mounted on the detent-lever 2 of the signal-transmitting mechanism. It may be explained that when the magnet E' is energized it attracts its armature, lifts the detent-lever 55 2, and sets in motion the clock mechanism which drives the ordinary break-contact

wheel 3 of the transmitting mechanism. It has not been deemed necessary to show all of this transmitting mechanism, as it is not new in this application and its specific character 60 informs no essential part of the present invention.

A shunt-circuit comprising conductors w and w' and the coils of the auxiliary magnet E' is controlled by a circuit-breaker B, to be 65 hereinafter more minutely described. The current enters the signal-box by a line-wire W, flows through the brushes 4 of the break-contact wheel 3, and thence by a wire w² to z, where it connects with the wire w of the shunt. If the shunt is open, as in Fig. 1, it then flows through the coils of magnet E' and by wire w' to the point z', thence by a wire w³ to the main magnet E, through the coils of 70 said magnet, and out by a line-wire W'. If, on the other hand, the shunt should be found closed at B, the current on reaching the point z will flow by wire w to a binding-post 5, thence to a contact-screw 6, thence to a movable or spring contact 7, thence to a binding-post 8, thence by wire w' to the point z', and 75 thence by the wire w³ to the main magnet E.

The armature 9 of the magnet E is carried by the upper arm of an armature-lever 10, fulcrumed at f, and on the lower arm of this 80 lever is rotatively mounted a gear-wheel 11. The armature 9 is retracted and the lever 10 rocked on its fulcrum by a spring 12. When the armature is retracted, as in Fig. 2, the wheel 11 is moved out of gear with a wheel 13 85 of an escapement driving mechanism M, and when the armature is attracted by its magnet, as in Fig. 1, the wheels 11 and 13 are put in gear for driving by the swinging of the wheel 11, as will be readily understood. On 90 the lateral face of the wheel 11 is a pin 14, which when said wheel rotates to the position seen in Fig. 1 impinges on the spring-contact 7 and moves it away from the screw-contact 6, thus breaking the shunt-circuit 95 which includes the coils of the magnet E'. The wheel 13 of the escapement driving mechanism drives the wheel 11 to effect the breaking of the shunt, and when the wheels 11 and 13 are thrown out of gear, as in Fig. 2, 100 the wheel 11 is rotated back again by a light spring 15 until its rotation is arrested by a stud 16 on the wheel engaging a fixed stop 17.

The retarded driving mechanism M is run by a spring in the usual way with clock mechanisms. The spring-case 18 is designated in the drawings somewhat diagrammatically.

The wheel 13 gears with a pinion 19 on the arbor of an escapement-wheel 20. The pallets 21 are carried by a lever 22, fulcrumed at *a*, and the balance-wheel 23 is actuated in a known way by the lever 22. On the armature-lever 10 is a third arm 24, which when the armature 9 is retracted is caused to impinge upon one arm of the escapement-lever 22 and hold the latter, as well as the entire driving mechanism, against movement.

The operation of the device will be readily understood from a brief explanation. If we suppose the parts to be at rest, as in Fig. 2, and the line is clear, then if the transmitting-button in the box be pressed the circuit will be closed through the line-magnet E, and its armature will be attracted, as seen in Fig. 1. This will set free the driving mechanism M, which will rotate the wheel 11 and cause its pin 14 to break the shunt about the magnet E'. This magnet will then lift the detent-lever 2, and thus set the transmitting mechanism in operation; but the escapement mechanism is also a retarder, and if at the time the transmitting-button of the box is pressed the line is not clear, because a signal is being sent from another box in the same system, then the current through the line-magnet E will be broken and closed at short intervals by the break-contact wheel at the other box; but at each break the armature 9 will be retracted, the wheels 11 and 13 thrown out of gear, and the wheel 11 will be rotated backward by its spring 15 until the stud 16 engages the stop 17. Hence the shunt about the auxiliary magnet E' will not be broken until the line is clear, when the signal will be transmitted in due course and in proper succession or sequence without the necessity of again pressing the transmitting-button.

The particular form of escapement is not important; but one important feature is the disengagement of the two gear-wheels at each break in the circuit, so that the wheel 11 may be returned to its normal position by its spring 15. It should be noted that when the detent-lever 2 is once lifted and the mechanism for transmitting the signal is thus set in motion the magnet E' becomes unimportant, as the mechanism will go on and send the signal without interference from it.

One important feature of the device herein shown is the employment of mechanical means for effecting the object to be attained in lieu of effecting it wholly by electrical means through an electromagnet. It will be noted that the only work required of the main or line magnet is to move or swing the wheel 11 into and out of gear with the driving mechanism and to arrest the vibrations of the escapement-lever, and these functions require very little electrical energy.

The invention is not limited or restricted to the special details of construction herein shown, as these may obviously be varied

without departing to any material extent from the invention. An essential is the employment of a movable device for breaking the shunt operatively connected with the lever of the armature of the line-magnet, whereby said device is moved out of operative relation with its driving mechanism when the armature-lever is retracted, and the device thus permitted to move back to its normal position.

In the drawings the break-contact wheel is shown, merely for convenience of illustration, with its brushes in the circuit with the magnets; but in practice this wheel has its brushes in a shunt which is broken by the lifting of the detent-lever 2.

Having thus described my invention, I claim—

1. A device for the purpose specified, having a main electromagnet in the line-circuit, an auxiliary electromagnet for setting in motion a signal-transmitting mechanism, said auxiliary magnet being in shunt in the circuit, a movable device for breaking the shunt about the auxiliary magnet when said device is moved to a predetermined extent, mechanism for moving said device, the armature and armature-lever of said main electromagnet, the latter operatively connected with said shunt-breaking device for putting the latter out of operative relation with its driving mechanism when said lever is retracted, means for retracting said lever, a stop for said shunt-breaking device, and means for returning the shunt-breaking device to said stop when said device is put out of operative relation with its driving mechanism.

2. A device for the purpose specified, having a main electromagnet in the line-circuit, an auxiliary electromagnet for setting in motion a signal-transmitting mechanism, said auxiliary magnet being in shunt in the circuit, a movable device for breaking the shunt about the auxiliary magnet when said device is moved to a predetermined extent, mechanism for moving said device, the armature and armature-lever of said main electromagnet, the latter operatively connected with said shunt-breaking device for putting the latter out of operative relation with its driving mechanism when said lever is retracted, means for retracting said lever, a stop for said shunt-breaking device, means for returning the shunt-breaking device to said stop when said device is put out of operative relation with its driving mechanism, and means carried by the armature-lever of the main magnet for arresting the said driving mechanism when said lever is retracted.

3. A device for the purpose specified, having a main electromagnet in the line-circuit, an auxiliary electromagnet in shunt in the circuit, the armature, its retracting means, and three-armed armature-lever 10, of the

main electromagnet, the retarded driving mechanism provided with a spur-wheel 13, the spur-wheel 11, rotatively mounted on one arm of the said armature-lever and so disposed as to be put into and out of gear with the driving-wheel 13 by the movements of the said lever, a stop device for said wheel 11, the spring 15 thereof, and the pin 14 in said wheel 11 so disposed as to break the shunt 10 about the auxiliary magnet.

4. A device for the purpose specified, comprising a main electromagnet and its armature, said magnet being in the line-circuit, means for retracting said armature, an auxiliary electromagnet normally shunted out 15 of the circuit, the armature of said auxiliary

magnet, the detent-lever of the signal-transmitting mechanism carrying the last-named armature, a normally closed shunt about said auxiliary magnet, a mechanical device 20 for breaking said shunt, a mechanical driver for actuating said shunt-breaking device, and means, actuated by the armature of the main electromagnet, for controlling the operation of said mechanical driver.

In witness whereof I have hereunto signed my name, this 22d day of March, 1905, in the presence of two subscribing witnesses.

PATRICK KENNEDY.
